SPRING

Theodor Held, Uerdingen, Germany, assignor to
the firm "Ringfeder" G. m. b. H., Uerdingen,
Germany

Application November 14, 1929, Serial No. 407,132,
and in Germany November 20, 1928

4 Claims. (Cl. 267—47)

My invention relates to improvements in springs, and more particularly in springs subject to bending stresses.

The object of the invention is to increase the strength of such springs by dimensioning them in accordance with the different behaviour of the material of the spring in regard to the frequently repeated tension and compression stresses. It is a well known fact that the fractures of leaf springs due to fatigue invariably start in the fibres subject to tension. This experience was further confirmed by extensive experiments and thorough researches in connection with the so-called ring springs consisting of superposed outer and inner rings which are subject to pure tension and compression stresses respectively. Here also the fatigue developed only in the outer rings subjected to tension while the inner rings at the same height subject to compression were almost indestructible. The risk of fracture due to the fatigue of the material may according to the present invention be greatly reduced and the endurance strength of springs subject to bending stresses increased by a judicious adaptation of the maximum tension and compression stresses to the properties of the material. In a spring rod subject to bending and the cross-section of which is divided in two symmetrical halves by the neutral fibres the tension and compression stresses are equal. If, on the other hand, by a change of the cross-section the neutral fibre is displaced from the middle towards the fibres subject to tension the maximum tension stresses are reduced for the same amount of bending while the maximum compression stresses increase. The ratio to be selected between tension and compression stresses depends upon the oscillation strength for these kind of stresses and thus changes with the material employed. The invention is, however, intended to cover all other spring sections subject to bending stresses in which the tension stresses are chosen lower than the compression stresses with the object of increasing the strength of the spring.

In the drawing affixed to my specification my invention is illustrated by way of example. In the drawing

Fig. 1 is a cross-section through an embodiment of my improved spring.

Fig. 2 is an elevation of a supporting spring for railroad vehicles.

Fig. 3 is a cross-section through Fig. 2, and

Figs. 4a and 4b are diagrams illustrating the nature of my invention.

Referring to the embodiment illustrated in Fig. 1 of the drawing it will be seen that the improved spring is composed of a plurality of layers in the manner of leaf springs which are provided in the part of the cross-section subjected to compression with one or more recesses A which in the form of grooves extend over the entire length of the leaf spring. These recesses A in the otherwise rectangular cross-section cause a displacement of the neutral fibre towards the part of the cross-section subject to tension. The neutral fibre passing through the center of gravity S is indicated by the fine line N—N. The distance e_1 of the most strongly stressed tension fibres is smaller than the distance e_2 of the most strongly stressed compression fibres from the line N—N so that the tension and compression stresses of the outer fibres stand in the ratio of $e_1:e_2$.

Figs. 2 and 3 show a railroad wagon spring in side-elevation and cross-section through the strap a holding the individual leaves b of the spring together. The outer clips c prevent the lateral displacement of the leaves in the customary manner.

It will be understood that any other suitable cross-sections may be chosen in which a greater strength of the springs is attained by differently dimensioning e_1 and e_2 .

The nature of the invention is diagrammatically illustrated in Figs. 4a and 4b. Besides a bending spring cross-section according to my invention such as for instance used for slotted inner rings of friction springs there is shown a ring piece in side-elevation which is subject to bending stresses. Here also S is the center of gravity, N—N the neutral fibre, e_1 the distance of the fibre subject to maximum tension and e_2 that of the fibre subject to maximum compression from the line N—N. The distribution of the stresses will be gathered from the line O—O located at right angles to N—N in conjunction with the line Z—D indicating the value and the nature of the stresses in the fibres. Since the stresses in all materials suitable for springs increase in proportion with the distance from the neutral fibre, the maximum tension k_2 must be smaller than the maximum pressure k_1 and stand in the relation of e_1 to e_2 .

I claim as my invention:—

1. A spring of a material having equal resistance to static tensile and compressive strains and having a cross-section formation in which the proportion of the distances of the outer tension fibres and the outer compression fibres from

the neutral plane substantially corresponds to the proportion of the endurance strengths under tension and compression stresses.

2. A spring of a material having equal resistance to static tensile and compressive strains and having a cross-section formation in which the proportion of the distances of the outer tension and compression fibres from the neutral fibres are substantially equal or smaller than 1:1, 2.

3. A spring as claimed in claim 1, in which the material of the cross sectional portion subject to compression, is taken out in the form of grooves.

4. A spring as claimed in claim 2, in which the material of the cross sectional portion subject to compression, is taken out in the form of grooves. 80
